UNITED STATES PATENT OFFICE.

HENRY MILLINGAR, OF MERCHANTVILLE, NEW JERSEY.

FLOWER-POT.

SPECIFICATION forming part of Letters Patent No. 681,066, dated August 20, 1901.

Application filed May 8, 1901. Serial No. 59,323. (No model.)

To all whom it may concern:

Be it known that I, HENRY MILLINGAR, a citizen of the United States, residing at Merchantville, in the county of Camden and State 5 of New Jersey, have invented a new and Improved Flower-Pot, of which the following is a specification.

It is the object of my invention to provide an improved flower-pot for temporary use. 10 The same is constructed of light or thin flexible material, preferably strips or sheets of wood which have a peculiar form adapting them to overlap and form a tapered pot. The 15 details of construction are as hereinafter described, and shown in the accompanying drawings, in which—

Figure 1 is a perspective view of my improved flower-pot. Fig. 2 is a plan view of the two parts composing the body of the pot, 20 the same being extended flatwise. Fig. 3 is an enlarged section on line 3 3 of Fig. 2.

The body of the pot is formed of two wooden pieces or sheets A and B, which are of like shape and connected by a detachable fastening a, applied at the center of the square portion b, forming the bottom of the pot. Each piece A and B has two enlarged end portions or wings c, whose sides are at an angle to each

other and whose ends are parallel. The said wings c are thus trapezoidal in shape, gradually increasing in width from the central portion b to the outer end. This shape is highly important, since it enables the wings c to overlap, as shown in Fig. 1, so that the pot has the desired taper. Thus in making 35 up the pot from the parts or pieces A and B, which may be shipped or stored in the flat, the wings c are bent upward and their edges overlapped and secured by wire or other fastenings d, as shown. Then a strip C of wood 40 or some other suitable flexible material is applied as a binding around the parts A and B adjacent to their upper edge and secured by suitable fastenings.

What I claim is—

As an improved article of manufacture, the flower-pot composed of two thin flexible sheets, having a square central portion and trapezoidal wings or end portions, which increase in width from the middle outward, 50 their side edges being overlapped and secured together as shown and described.

HENRY MILLINGAR.
